United States Patent Office

Des. 178,436
Patented July 31, 1956

178,436

PULL

Charles C. Unzicker, Rockford, Ill., assignor to Amerock
Corporation, a corporation of Illinois

Application June 10, 1954, Serial No. 30,894

Term of patent 14 years

(Cl. D10—8)

Fig. 1

Fig. 2

Fig. 3

Fig. 2 is a side view.

Fig. 3 is a top view of the pull.

Fig. 4 is a rear elevational view of the pull.

I claim:

The ornamental design for a pull, substantially as shown.
